UNITED STATES PATENT OFFICE.

RAYMOND W. CURRAN, OF KANSAS CITY, MISSOURI.

ORDER-CARRYING HOOP AND HOLDER THEREFOR.

Application filed November 15, 1926. Serial No. 148,462.

This invention relates to a hoop and holder therefor which are combined to make up a device especially adapted for use by station agents of a railroad and has for its primary object the provision of improvements and refinements in construction which render the hoop easily removable by a quick jerk and which makes the holder and hoop cheap to make and extremely strong and durable in construction.

Heretofore devices of this character have been made up of a large number of complicated parts which readily get out of order and which render the device expensive to manufacture. Often times a large number of small springs are used in the holding device and when this holder becomes inoperative it is impossible to releasably support the message carrying hoop where it can be received by a trainman as the train passes the station.

The preferred form of the invention is shown in the accompanying drawing, in which

Figure 1 is a side view of a hoop holder showing the order carrying hoop in place;

Fig. 2 is an enlarged fragmentary vertical section through the holder taken on the dividing line between the two members making up the head of the holder;

Fig. 3 is another enlarged vertical section taken on line III-III of Figure 1; and

Fig. 4 is a horizontal cross section taken on line IV-IV of Fig. 2 both members being shown.

Similar reference characters refer to like parts in the several views and the numeral 5 designates an ordinary long wooden handle or the like which may be of any desired length and which supports the holder head proper which is made up of two castings 6 and 7 and which are securely held on one end of the handle 5 by rivets or analogous means 8 which pass through the lower portion of each casting 7. This lower portion is semi circular in cross section as shown at 9 and the cooperating portions 9 entirely surround the supporting end of handle 5. The castings 6 and 7 are identical and each is provided with a pair of co-acting partitions 10 which are pressed inwardly from the main side wall of each casting in such a way that the head of the holder when assembled is divided into an upper and a lower compartment joined by a comparatively nar-

row passage formed between the partitions 10. These partitions should have their upper walls inclined as shown at 12 and the inner end of the V-shaped partitions 10 should be rounded as shown in Fig. 2. These partitions 10 are formed by pressing a portion of the respective casting inwardly from the main side wall. In doing this, a pair of depressions are formed as shown in Figure 1. When the two castings 6 and 7 which form the head proper are riveted together along the edges by rivets or like means 13 the upper inclined walls 12 of the partitions cooperate to guide the hoop salient downwardly and inwardly toward the passage 70 formed between the inner ends of the V-shaped partitions.

A specially constructed hoop is used with this holder which hoop may consist of body portion 14 which carries the well known spring clip 15 beneath which may be affixed a folded sheet of paper having the train order written thereon. To permit the hoop to be held by this novel holder the same should have an integral salient projecting outwardly from the body portion 14, which salient has a pair of waved sides 16. These sides converge toward each other as their outer ends are approached and the arcs formed by the waving of the sides adjust 80 themselves to the rounded inner end of each partition 10, as shown in Fig. 2. When the hoop is inserted in the holder, the salient is pushed into the upper chamber formed within the head and thence forced between partitions 10 through the narrow passage to a place where an arc of each side engages the inner ends of the partitions as clearly illustrated. This act will slightly contract the body of hoop 14 and the same is removably 95 retained in such a manner that a quick jerk will instantly pull the salient formed in the hoop 14 from between partitions 10. It is obvious that this hoop may be quickly inserted into the holder and that it will be securely and releasably retained therein until the proper moment arrives when it is to be jerked from the held position.

Having thus described the invention, what I claim and desire to secure by Letters Patent is:

1. A device of the kind described comprising in combination, a hoop holder and a message carrying hoop having means for releasably gripping a message, said holder in-

cluding a chambered head, means including a pair of co-acting V-shaped partitions within said head for guiding the message carrying hoop to the gripped position, said hoop being formed to present a salient having a plurality of arcs adapted to be engaged by said guiding means and V-shaped partitions whereby the sides of the salient are drawn closer together and yieldably held as the hoop is forced to the held position.

2. A device of the kind described comprising in combination, a hoop holder and a message carrying hoop having means for releasably gripping a message, said holder including a chambered head having a pair of downwardly and inwardly extending inclined partitions therein, said hoop being formed to present a salient having sides converging toward each other as their outer ends are approached, said partitions being adapted to engage the sides of said salient

to press the same together as the hoop is moved to the held position.

3. A device of the kind described comprising in combination, a hoop holder and a message carrying hoop having means for releasably gripping a message, said holder including a chambered head having partitions therein to form an upper and a lower chamber joined by a relatively narrow passage, said hoop being formed to present a salient having sides converging toward each other as their outer ends are approached, each side having a series of arcs formed therein and engageable by the closest portions of said partitions, whereby the arcs are forced toward each other when the hoop salient enters said passage.

In testimony whereof I hereunto affix my signature.

RAYMOND W. CURRAN.
